UNITED STATES PATENT OFFICE

HANS KARL KLOESS, OF HAMBURG, GERMANY

HULL CONSTRUCTION

Application filed September 10, 1927, Serial No. 218,678, and in Germany May 21, 1927.

My invention relates to the designing of ships' hulls and has for its object to improve the method of designing.

The invention is based on the observation that in order to reduce the resistance to the forward movement of a ship, the water which as the ship moves ahead accumulates and is dammed up at the bow, should be given an opportunity to flow off rapidly and smoothly 10 backwards and with the least possible resistance, that is to say, along the shortest possible paths. In order to attain this object, I so arrange the frames of the vessel which are parallel to each other in the bow and the stern 15 of the vessel that they form an angle with the horizontal, the frames in the bow of the vessel preferably forming a larger angle than the frames in the stern.

Reference is made to Figs. 1 and 2 of the 20 accompanying diagrammatic drawing showing by way of illustration the principle herein involved, the frames being indicated in the usual manner.

In the drawing, only the portion of the 25 hull below the water-line of the vessel is indicated, said water-line being designated by the line W—W. The lines A and A₁, including the broken lines, designate the side-walls of the central portion of the hull, while B indicates the bottom line. O—O₁ is the longitudinal symmetrical plane of the vessel. As 30 shown in the drawing, the bottom line B forms with the lines A and A₁ and the water-line W—W a rectangle, of which O, O₁ is the 35 symmetrical plane. A line drawn from O to either O₂ or O₃ and marked in the drawing S₀ constitutes the principal diagonal of the vessel, while the lines K and K₁ are the bilge lines. Thus, the lines B, K and A and B K₁, 40 and A₁ respectively indicate the master frame of the vessel.

As appears from Fig. 1 of the drawing the 45 frames S_{p1}, S_{p2} are parallel to each other and to the lines K and K₁. With a view of decreasing the resistance, the edges resulting from this construction may be rounded off as indicated by the small rounded broken line at the right hand lower side of Figs. 1 and 2.

50 Fig. 2 represents a modified embodiment of

the invention which is particularly distinguished by the fact that the inclination of the frames in the bow of the vessel relative to the horizontal as represented by the bottom-line B is different from the inclination in the stern. One half of the figure shows the inclination of the frames at the bow, and the other half the inclination of the frames at the stern, the frames of the stern shown on the left of Fig. 2 being less steeply inclined 55 than the frames at the bow shown on the right of Fig. 2, which arrangement is a useful expedient to prevent the stern of the vessel from sinking too deep into the water in the case of very high velocities. 60

In Fig. 2, the angle formed by the frames at the bow of the vessel with the horizontal is designated α_1 while the angle formed by the frames at the stern of the vessel with the horizontal is designated α_2 . The dash-and-dot lines on the left half of Fig. 2 indicate the position of the frames at the bow of the vessel, while the full lines S_{p3} and S_{p4} indicate the position of the frames at the stern of the vessel. 75

While I have described the invention with reference to certain particular embodiments, I desire that it be understood that modifications may be made, and that no limitations upon the invention are intended other than 80 those imposed by the scope of the appended claim.

I claim:—

In the hull construction of a sea-vessel, the combination of groups of frames parallel to 85 each other as to each group, the frames included in the group at the bow of the vessel being inclined relative to the horizontal at a larger angle than the frames included in the group at the stern of the vessel. 90

In testimony whereof I have affixed my signature.

HANS KARL KLOESS.
